UNITED STATES PATENT OFFICE.

HENRY VON PHUL THOMAS, OF KIRKWOOD, MISSOURI, ASSIGNOR TO KILLARK ELECTRIC MANUFACTURING COMPANY, OF ST. LOUIS, MISSOURI, A CORPORATION OF MISSOURI.

FUSE-PLUG.

1,225,890.

Specification of Letters Patent. Patented May 15, 1917.

Application filed May 15, 1916. Serial No. 97,582.

To all whom it may concern:

Be it known that I, HENRY VON PHUL THOMAS, a citizen of the United States, residing at Kirkwood, county of St. Louis, 5 State of Missouri, have invented a certain new and useful Improvement in Fuse-Plugs, of which the following is a specification, reference being had to the accompanying drawings, forming a part thereof.

10 This invention relates generally to thermal cut-outs and, more especially, to a certain new and useful improvement in that type of cut-outs commonly known as fuse-plugs.

15 As heretofore generally constructed, so far as I am aware, cut-outs of the type stated comprise a chambered or cup-shaped so-called body-member of insulating material, a screw-threaded contact-member or shell for engagement with the usual socket, this shell surrounding or inclosing the lower portion of the body-member, a cover consisting of an insulation-disk and a flanged metallic ring or apertured cap for holding the 20 disk flatwise against the outer or upper end of the body-member, and the usual fusible element. The cover comprising the insulation-disk mentioned is employed mainly for the purpose of preventing particles of the 25 fusible element, on a blowing or fusing thereof, escaping from the otherwise open end of the so-called body-member and thereby possibly causing fires or other accidents; and in order that the condition of 30 the fusible element of the plug may be at all times visually observed, this disk is usually of mica or other transparent insulation material. For purposes of description, this insulation disk may hence be well called 35 the window of the fuse or plug. In fuses of this type, it is essential that the shell and cover or window be each securely fixed or fastened upon the body-member, so that the cover may resist and not be blown off under 40 explosive stresses on a rupture of the fusible element, and that the shell may resist shearing or other stresses to which it may be subjected on the plug being seated in or removed from its socket. Hence, in the production or manufacture of plugs or fuses of 45 this class comprising, as heretofore, the several parts stated, the cover and shell are necessarily each separately and independently one from the other fastened to and 50 upon the so-called body-member; consequently, because of the said separate parts and the several operations gone through with in operatively assembling the same, the cost of production or manufacture of such plugs is correspondingly relatively 55 high.

55 The principal object of the present invention is to obviate many of the parts and assembling operations now required in the production and manufacture of fuses of this 60 type and to simplify and generally improve upon, and cheapen the cost of production or manufacture of, fuses of the class described.

65 To the end stated and with the above and other objects in view, my invention resides 70 in the provision of a fuse-plug comprising a member adapted to provide not only a so-called shell for engagement with the usual socket, but also a rigid retainer for the mica-disk or other window of the plug, this combination-member being conveniently and 75 with ease and at slight expense so operatively fitted or mounted upon and engaged or interlocked with the insulation member of the plug to adequately resist and overcome 80 any explosive, shearing, or other strains or stresses to which the plug may in use be subjected and which may tend to mechanically rupture the plug. By the employment of my new combined socket-engaging and window-retaining member, I 85 hence provide at comparatively low cost and expense a most efficient fuse of the type described.

90 My new combined socket-engaging and window-retaining member, I have found from experience, may have different forms and structural shapes and may be variously incorporated or embodied in the finished plug. As illustrating my invention, I have 95 accordingly shown in the accompanying drawings several different types of my new combined socket-engaging and window-retaining member and of fuse plugs embodying the same, but it is to be understood that 100 my combined socket-engaging and window retaining member, as well as fuse plugs embodying the same, may have other forms without departing from the nature and spirit of my invention.

105 In the accompanying drawings, wherein, as stated, I have illustrated several embodiments of my invention,

Figures 1 and 2 are, respectively, plan and side elevational views of a fuse plug embodying what may be described as the preferred form of my invention;

5 Fig. 3 is a vertical sectional view of the same taken approximately on the line 3—3, Fig. 1;

Fig. 4 is an inverted plan view thereof;

10 Fig. 5 is a perspective view of the combined socket-engaging and window-retaining member of this form or embodiment of my invention;

15 Figs. 6 and 7 are, respectively, plan and side elevational views of a fuse plug embodying a slightly modified form of my invention;

Fig. 8 is a vertical sectional view of the same taken approximately on the line 8—8, Fig. 6;

20 Fig. 9 is an inverted plan view thereof;

Figs. 10 and 11 are, respectively, plan and side elevational views of a fuse plug embodying a second slightly modified form of my invention;

25 Fig. 12 is a vertical sectional view of the same taken approximately on the line 12—12, Fig. 10;

Fig. 13 is an inverted plan view thereof;

30 Figs. 14 and 15 are perspective views of the parts which when fixed together upon the insulation member of the plug comprise the combination socket-engaging and window-retaining member of this form of my invention;

35 Figs. 16 and 17 are, respectively, plan and side elevational views of a fuse plug embodying a third slightly modified form of my invention;

40 Fig. 18 is a vertical sectional view of the same taken approximately on the line 18—18, Fig. 16;

45 Fig. 19 is a side elevational view of the combination socket-engaging and window-retaining member of this form of my invention;

50 Fig. 20 is a perspective view of the insulation member of this form of my invention;

Figs. 21 and 22 are, respectively, plan and 55 side elevational views of a fuse plug embodying a fourth slightly modified form of my invention;

Fig. 23 is a vertical sectional view of the same taken approximately on the line 23—23, Fig. 21;

59 Fig. 24 is an elevational view of the combination socket-engaging and window-retaining member of this form of my invention;

60 Fig. 25 is a perspective view of the insulation member of this form of my invention;

Figs. 26 and 27 are, respectively, plan and side elevational views of a fuse plug embodying a fifth slightly modified form of my invention;

Fig. 28 is a vertical sectional view of the same taken approximately on the line 28—28, Fig. 26;

65 Fig. 29 is a side elevational view of the insulation member of this form of my invention; and

70 Fig. 30 is a fragmentary perspective view of the combined socket-engaging and window-retaining member of this form of my invention.

75 Referring now particularly to the form of my invention illustrated in Figs. 1 to 5, both inclusive, 1 indicates that part of the plug which I will call the insulation-member. This member 1 may be of any 80

suitable shape and may be described as being an electrically insulating body which supports the center bottom contact-button, member 1 also forming the lining and nucleus for the socket-engaging member and 85

providing the seat for the inclosing window. As here shown, member 1 is substantially a cup-shaped or cylindrical chambered section or piece of porcelain, fiber, or the like mold- 90

ed or otherwise formed into the desired shape. At its lower or integrally closed end, member 1 is provided with the usual 95

center-contact 2, electrically contacting or engaging with which within member 1 is one end of the usual fusible element 3. At 100

its upper end, member 1 is preferably integrally enlarged to provide an overhanging annulus or collar 4 adapted to serve as a hand or finger-grip for the plug, whereby 105

the plug may with safety be seated in or removed from its coöperating socket, not shown. At its upper end also, member 1 is 110

cut away or counterbored to provide a seat upon which, within collar 4, flatwise fits a window-disk 5 of mica or other suitable 115

transparent insulation material. At the base of its said cut-away or counterbored portion, member 1 is cut away longitudinally to provide preferably a pair of diamet- 120

rically opposite arcuate slots 6, the inner 110 walls of which slots are approximately flush or in alignment with the outer surface of the lower or reduced portion of member 1.

A indicates the combination socket-eng- 125

gaging and window-retaining member of the plug. This member A, which is of suit- 130

able metallic material, preferably integrally comprises a ring 7 adapted to fit upon the upper end of member 1 within collar 4 and over insulation-disk or window 5, and dia- 135

metrically opposite legs 8, approximately arc-shaped in cross section, adapted to project through the slots 6 and along the outer surface of the lower or reduced portion of member 1, as shown. Through the greater 140

portion of their length, legs 8 are spirally crimped or otherwise suitably formed to 145

provide screw-threads 9 for engagement with the usual threaded-socket. Member A being 150

so arranged upon insulation-member 1, 155

being arranged upon insulation-member 1, 160

legs 8 at their lower or free ends are flanged, spun, or otherwise locked, as at 10, under insulation-member 1, and member A thereby securely fastened upon insulation-member 1; and, when so fastened or fixed upon insulation-member 1, member A provides, as will be observed, not only a so-called shell for engagement with the usual socket, but also a retaining member for the window 10 or disk 5. At its upper end, fusible element 3 is suitably projected through member 1 to electrically engage or contact with metallic member A. The finished plug may be readily and cheaply produced, practically 15 but one operation being required in the operative assembling of insulation-member 1, disk 5, and socket-engaging and window-retaining member A.

In the modified form of my invention 20 illustrated in Figs. 6 to 9, both inclusive, 1^b indicates the insulation-member of the plug, which is similarly substantially a cup-shaped or cylindrical chambered section of porcelain, fiber, or the like, 2 is the center-contact, and 3 the fusible element. At its upper end, insulation-member 1^b is counterbored to provide 25 a seat, as at 18, for the usual insulation-disk or window 5. At its upper end also, insulation-member 1^b is cut away transversely, as at 19, to provide a plurality of spaced battlements or the like 20 adapted to serve as 30 a hand or finger-grip for the plug, whereby the plug may conveniently be seated in or removed from its socket. D is the combination socket-engaging and window-retaining 35 member of this plug. This member B, which is of suitable metallic material, preferably integrally comprises a ring 11 and an approximately cylindrical or tubular body-portion or shell 12, the member B being adapted to tightly 40 inclose or incase the insulation-member 1^b as shown, with its ring 11 fitting upon the upper end of member 1^b over the window or disk 5. Member B, in the operative assembling of 45 the parts of this plug, being endwise slipped 50 into operative position upon insulation-member 1^b, the lower end of its tubular portion 12 is similarly spun or flanged, as at 13, under member 1^b and the parts thereby 55 securely fastened or locked together. When so fastened or fixed together, the member B similarly provides a socket-engaging and 60 window retaining member for the plug, the tubular portion 12 of member B being also spirally crimped or otherwise formed to provide 65 screw-threads 14 for engagement with the usual threaded socket. The fusible element 3 is similarly at its upper end projected through insulation-member 1^b to electrically contact or engage with metallic 70 member B.

In the second modified form of my invention illustrated in Figs. 10 to 15, both inclusive, 1^c is the insulation-member, which is approximately similar to insulation-member 1^b, 2 is the center-contact, and 3 is the fusible element. 5 is the usual insulation-disk or window. Tightly encircling insulation-member 1^c and having its lower end spun or flanged thereunder, as at 15, is a 85 metallic spirally crimped or otherwise

threaded socket-engaging shell 16. Extending across the upper end of insulation-member 1^c over window or disk 5, is a metallic window-retaining strip 17, strip 17 at its opposite ends being bent downwardly to project longitudinally of insulation-member 1^c and being soldered or otherwise electrically fixed to shell 16. Shell 16 and strip 17 thus form the combination socket-engaging and window-retaining member C of the plug, the parts being easily and cheaply operatively assembled and the plug inexpensively produced.

In the third modified form of my invention illustrated in Figs. 16 to 20, both inclusive, 1^d is the insulation member, which is likewise preferably a cup-shaped or cylindrical chambered section of porcelain, fiber, or the like, 2 is the center-contact, and 3 the fusible element. At its upper end, insulation-member 1^d is counterbored to provide a seat, as at 18, for the usual insulation-disk or window 5. At its upper end also, insulation-member 1^d is cut away transversely, as at 19, to provide a plurality of spaced battlements or the like 20 adapted to serve as 80 a hand or finger-grip for the plug, whereby the plug may conveniently be seated in or removed from its socket. D is the combination socket-engaging and window-retaining 85 member of the plug. This member D, which is of suitable metallic material, comprises a spirally crimped or otherwise threaded cylindrical or tubular open-ended shell 21 adapted to fit tightly upon and around insulation-member 1^d, as shown. At its upper 90 end, shell 21 is provided with a plurality of spaced projections or lips 22. Shell 21 being endwise slipped upon insulation-member 1^d, its projections or lips 22 are brought 95 into register with the spaces 19 between battlements 20 and bent inwardly over the upper end of insulation-member 1^d upon window or disk 5, and the lower end of shell 21 spun or flanged, as at 23, under the lower 100 end of insulation member 1^d, the parts being thereby securely fixed together and the shell 21 thus providing not only a socket-engaging, but also a window-retaining, member 105 for the plug. In this form of plug also, the parts may be readily assembled and the plug produced at relatively slight expense, the fusible element 3 at its upper end being suitably projected through insulation-member 1^d to electrically engage with the metallic 110 shell 21.

In the fourth modified form of my invention illustrated in Figs. 21 to 25, both inclusive, 1^e is the insulation-member, which is likewise preferably a cup-shaped or cylindrical chambered section of porcelain, fiber, or the like, 2 is the center-contact, and 3 the fusible element. At its upper end, insulation-member 1^e is counterbored to provide a seat, as at 24, for the usual insulation-disk 125 130

- or window 5. At its upper end also, insulation-member 1° is cut away, as at 25, to provide a pair of diametrically opposite arc-shaped battlements or the like 26 adapted to 5 serve as a hand or finger grip for the plug, whereby the plug may be conveniently seated in or removed from its socket. E indicates the combination socket-engaging and window-retaining member of the plug.
- 10 This member E, which is likewise of suitable metallic material, comprises a spirally crimped or otherwise threaded cylindrical or tubular open-ended shell 27 adapted to tightly fit upon and around insulation-member 1° as shown. At its upper end, shell 27 is provided with a pair of diametrically opposite projections or lips 28—28', one of which, as, for instance, lip 28, is provided with an apertured circular extension or ring 29. Shell 27 being endwise slipped upon insulation-member 1°, its lips or projections 28—28' are fitted in the spaces 25 between battlements 26 and bent inwardly over and upon the upper end of insulation-member 25 1°, ring 29 then extending flatwise over and upon disk or window 5 and being preferably soldered or otherwise electrically fixed to opposite lip 28'. The lower end of shell 27 is also spun or flanged, as at 30, under the 30 lower end of insulation-member 1°, the parts being thereby securely fixed together and the shell 27 likewise providing both a socket-engaging and window-retaining member for the plug. This form of plug may also be 35 readily manufactured at comparatively low cost, the fusible element 3 at its upper end being suitably projected through insulation-member 1° to electrically engage with the metallic shell 27.
- 40 In the fifth modified form of my invention illustrated in Figs. 26 to 30, both inclusive, 1° is the insulation-member, which again is preferably a cup-shaped or cylindrical chambered section or piece of porcelain, fiber, or the like; 2 is the center-contact, and 3 the fusible element. Fitting flatwise upon the upper end of insulation-member 1° is the usual insulation-disk or window 5, and also fitting upon the upper end of insulation-member 1° and upon disk or window 5, is a flanged centrally apertured cap 31. Upon its outer surface and throughout preferably the greater part of its length, insulation-member 1° is spirally grooved, as at 32. 45 At its upper end, insulation-member 1° is further provided upon its surface with a pair of approximately diametrically opposite vertically-disposed grooves 33 continuous with, or leading into, spiral groove 32, these grooves 32—33 being adapted to provide a seat for the combination socket-engaging and window-retaining member of the plug, which is here preferably in the form of a one-piece wire F approximately 50 semi-cylindrical in cross-section. This wire F is suitably fixed at its lower end to insulation-member 1° adjacent the base thereof, is then seated in groove 32 and spirally wound around insulation-member 1°, then carried through one groove 33 up, over, and across the upper end of insulation-member 1° upon cap 31, and then bent downwardly upon the opposite side of insulation-member 1° into opposite slot 33, its free end being soldered or otherwise electrically connected with the upper coil or strand of the wire. The spirally wound and fixed wire F thus provides both a socket-engaging and window-retaining member for the plug, this plug embodying my invention being also 55 easily manufactured or produced and at slight cost.
- 60 Thus, throughout the several described embodiments of my invention, it will be seen that I provide an efficient fuse plug of few parts and the parts of which may with ease and convenience and practically at one operation be operatively assembled, thereby simplifying the construction of plugs of this type and cheapening the cost of production.
- Having thus described my invention, what I claim and desire to secure by Letters Patent is:
1. A fuse plug or the like including a combined socket-engaging and window-retaining member.
  2. A fuse plug or the like including an insulation-member, an insulation-window, and a metallic-member fixed upon the insulation-member and including a window-retaining portion, the metallic-member adapting the plug for engagement with a socket and its said window-retaining portion engaging upon said window to retain the same in operative position upon the insulation-member.
  3. A fuse plug or the like including a chambered insulation-member, an insulation-window fitting flatwise upon the insulation-member and providing a closure for its said chamber, and a metallic-member fixed upon the insulation-member, said metallic-member having a portion adapting the plug for engagement with a socket and a portion engaging upon the window to retain the same in operative position upon the insulation-member.
  4. A fuse plug or the like including a cylindrical chambered insulation-member, an insulation-disk fitting flatwise upon the insulation-member and providing a closure for its said chamber, and a metallic member fixed upon the insulation-member, said metallic-member having a partly threaded portion adapting the plug for engagement with a threaded socket and a portion engaging upon said disk to retain the same in operative position upon the insulation-member.
  5. A fuse plug or the like including a cy-

- lindrical chambered insulation-member, an insulation-disk fitting flatwise upon the insulation-member and providing a closure for its said chamber, and a partly threaded 5 metallic-member fitting upon, and engaging at opposite ends with, the insulation-member, the metallic-member adapting the plug for engagement with a threaded socket and retaining said disk in operative position 10 upon the insulation-member.
6. A fuse plug or the like including a cylindrical chambered insulation-member, an insulation-disk fitting flatwise upon the insulation-member and providing a closure for 15 its said chamber, and a partly threaded metallic-member fitting upon the insulation-member and locked at one end thereunder, the metallic-member adapting the plug for engagement with a threaded socket and retaining 20 said disk in operative position upon the insulation-member.
7. A fuse plug or the like including a cylindrical chambered insulation-member, an insulation-disk fitting flatwise upon the insulation-member and providing a closure for 25 its said chamber, and a partly threaded metallic member fitting upon the insulation-member and locked at one end thereunder, the metallic-member adapting the plug for 30 engagement with a threaded socket and comprising a ring fitting upon the disk to retain the same in operative position upon the insulation-member.
8. A fuse plug or the like including a cylindrical chambered insulation-member, an insulation-disk fitting flatwise upon the insulation-member and providing a closure for 35 its said chamber, and a metallic-member fitting upon the insulation-member and comprising an apertured portion and partly threaded leg-portions, said apertured portion engaging upon said disk to retain the same in operative position upon the insulation-member and said leg-portions being 40 locked at one end to the insulation-member and adapting the plug for engagement with a threaded socket.
9. A fuse plug or the like comprising a cylindrical chambered insulation-member provided with an overhanging collar, an insu- 45
- lation-disk seated upon the insulation-member within said collar and providing a closure for the chamber of the insulation-member, the insulation-member being also provided with a plurality of arculate slots, and a metallic-member fitting upon the insulation-member and including a ring and partly threaded legs, said ring engaging upon the upper end of the insulation-member over said disk and said legs projecting 50 through said slots and lengthwise along the insulation-member, said legs being locked at one end under the insulation-member and adapting the plug for engagement with a threaded socket. 55
10. In a fuse plug or the like, a chambered insulation-member and a window on the insulation-member for its said chamber, in combination with a metallic-member that is engageable with the insulation-member of the plug, said member including a portion adapted to lock the window of the plug upon the insulation-member and a portion adapted for threaded engagement with a 60 socket. 65
11. In a fuse plug or the like, a chambered insulation-member and a window on the insulation-member for its said chamber, in combination with a metallic member that is adapted to engage with and upon the opposite ends of the insulation-member of the plug to lock the window of the plug upon the insulation-member and adapt the insulation-member for threaded engagement with a socket. 75
12. A metallic-member for fuse plugs and the like that is adapted to engage with and upon opposite ends of the insulation-member of the plug, said member including a partly threaded portion and an apertured portion. 80
13. A metallic-member for fuse plugs and the like that is adapted to engage with and upon the opposite ends of the insulation-member of the plug, said member including a ring and partly threaded legs. 85

In testimony whereof, I have signed my name to this specification.

HENRY VON PHUL THOMAS.
